UNITED STATES PATENT OFFICE.

HERBERT ABRAHAM, OF NEW YORK, N. Y., ASSIGNOR TO THE STANDARD PAINT COMPANY, A CORPORATION OF NEW JERSEY.

SHINGLE.

1,385,809.

Specification of Letters Patent.

Patented July 26, 1921.

Application filed December 1, 1919. Serial No. 341,791.

To all whom it may concern:

Be it known that I, HERBERT ABRAHAM, a citizen of the United States, residing at the city, county, and State of New York, have 5 invented certain new and useful Improvements in Shingles, of which the following is a specification.

This invention relates particularly to shingles composed of the material commonly 10 called "prepared roofing."

Such shingles are made of bituminized fabric surfaced with particles of mineral matter and generally have an overall dimension of 8 by 12 $\frac{3}{4}$ inches. According to the 15 approved practice they are laid in overlapping courses with 4 inches of each shingle exposed to the weather. Unless great care is exercised in properly locating and nailing the shingles they are apt to be laid irregularly 20 thereby giving the roof an unsightly appearance and not affording the best protection against inroads of the weather.

The principal object of the invention is to 25 provide shingles having surface markings indicating the extent which is to be exposed to the weather when the shingles are laid and the location of the points at which the nails are to be driven in fastening the shingles to a roof deck.

30 In laying the shingles, in order to expose the proper amount of shingle material to the weather and to produce a regular and attractive appearance of the roof, it is merely necessary to register the lower edge of each 35 overlying shingle with the marking on the underlying shingle and to drive the nails at the indicated points.

In the accompanying drawings, where- 40 in I have illustrated a preferred embodiment of my invention,

Figure 1, is a plan view of one of my improved shingles, and,

Fig. 2, is a perspective view of a section of a roof laid with such shingles.

45 Referring to the drawing, 1 indicates an ordinary prepared roofing shingle having its surface coated in the usual manner with particles of crushed slate or other surfacing material. If desired the two ends of the 50 shingle may be coated with differently colored material as in the case of the ordinary multi-colored shingle.

55 My improvement consists in the provision of a band 2, of contrasting color, preferably black, extending transversely across

the face of the shingle and spaced from the top and bottom edges a distance equal to the extent to be exposed to the weather when the shingle is laid. In the standard shingle, which is approximately 8 by 12 $\frac{3}{4}$ inches in 60 dimension, the edges of the band will be disposed approximately 4 inches from the top and bottom of the shingle in order to expose the proper amount of shingle material.

Suitable markings, such as the notches 3, 65 are provided to indicate the correct location of the nailing points. It will be understood that in fastening each shingle only two nails are used but that the shingle is marked with four nailing points so that it may be reversible, that is, so that it may be laid with 70 either end exposed to the weather.

In laying the shingles, as shown in Fig. 2, the lower ends of the overlying row of shingles A are alined with the lower edges 75 of the bands 2 of the underlying row B, and then the nails 4 are fastened at the points indicated by the markings 3. In this manner the shingles are properly located to give the roof a regular and slightly appearance 80 and to expose the correct amount of shingle material to the weather. From an inspection of Fig. 2 it will be seen that the shingles of each row are spaced apart, generally 85 $\frac{1}{2}$ inch, and that a portion of the bands 2 of the underlying row of shingles is exposed in each space. As the color of the bands contrasts with that of the ends of the shingles a desirable shadow effect is produced which gives an illusory appearance of increased 90 depth or thickness of the roofing.

While I have illustrated and described herein a preferred form of my improved shingle, it will be understood that various changes and modifications may be made 95 therein without departing from the scope of the invention.

What I claim is:

1. A shingle composed of bituminized fabric having a band of contrasting color 100 adherently applied to its weather surface, positioned midway between its upper and lower edges and spaced therefrom a distance equal in extent to that which the shingle will be exposed when laid.

2. A shingle composed of bituminized fabric having a band of contrasting color 105 extending transversely across its weather surface, the edges of the band being indented at spaced points to indicate nailing 110

places, said edges being spaced equally from the upper and lower shingle edges, whereby to serve as gages for laying the shingle with either edge exposed.

5. 3. A shingle composed of bituminized fabric having a band of dark color intermediate its upper and lower edges and spaced equally therefrom, and which when laid will simulate the appearance of shadows in the spaces intervening adjacent shingles.

- 10 4. A shingle composed of bituminized

fabric having its weather surface coated with particles of mineral matter, to which is applied a band of contrasting color spaced equally from the upper and lower shingle 15 edges, and indented at spaced points to indicate nailing places.

5. A shingle composed of bituminized fabric having a transverse band of contrasting color on its weather surface intermediate the shingle ends. 20

HERBERT ABRAHAM.
